CLAIM

The ornamental design for a valve guard for a gas cylinder, as shown and described.

DESCRIPTION

FIG. 1 is a top isometric view of a valve guard for a gas cylinder.

FIG. 2 is a front view of the valve guard for a gas cylinder.

FIG. 3 is a rear view of the valve guard for a gas cylinder.

FIG. 4 is a side view of the valve guard for a gas cylinder; and,

FIG. 5 is a side view of the valve guard for a gas cylinder, showing the side opposite of that shown in FIG. 4.
